UNITED STATES PATENT OFFICE.

THOMAS L. JURASINSKI, OF WEST ALLIS, WISCONSIN.

WINDOW STRUCTURE.

Application filed February 9, 1925. Serial No. 8,081.

My invention relates to improvements in window structures and has to do more particularly with the provision of means designed to render the same tight against the passage of the elements therethrough between the sash or sashes and the frame. It also contemplates the provision of means at the joints between the frame sections for a similar purpose and it is to embody such means in an inexpensive structure capable of association with ordinary types of windows both sliding and swinging without material alterations thereto that constitutes the purpose of my invention.

With the foregoing and other purposes in view my invention consists in the novel features of construction, combination and relative arrangement of parts as will be hereinafter more fully described, illustrated in the accompanying drawings and particularly defined in the appended claims.

In the drawings wherein like characters of reference denote corresponding parts in the different views:

Figure 1 is a vertical transverse section through a window embodying the novel characteristics of my invention.

Figure 2, a front elevation of the window as illustrated in Figure 1.

Figure 3, an enlarged fragmentary section on the line 3—3 of Figure 1.

Figure 4, a front elevation of a window having a hinged sash and equipped with my improvements.

Figure 5, a fragmentary section on the line 5—5 of Figure 4, and

Figure 6, a fragmentary section on the line 6—6 of Figure 4.

Referring now to the drawings in detail, particularly to Figures 1, 2 and 3, it will be observed that my improvements presently to be referred to are associated with a window structure of ordinary design consisting of a frame 10 within which upper and lower sashes 11 and 12, respectively, are slidably arranged. The frame 10 includes vertically disposed side pieces 13 connected at their upper ends by a transverse connecting piece 14 and at their lower ends by a transverse piece 15 upon which rests the sill 16. Devices 17 are provided at the joints between the outer side pieces 13 and the transverse pieces 14 and 15 to prevent the passage of the elements therethrough. Said devices 17 are all of the same construction, each in-

cluding a flat terminal outer portion 18, a doubled inner portion 19 and an intermediate portion 20 connecting said inner and outer portions, which latter extend from the intermediate portion relatively in opposite directions as shown. The doubled portions 19 are adapted to be received in recesses formed in the respective ends of the vertical side pieces 13 in which position the outer portions 18 will be disposed flat against the upper and lower transverse connecting pieces 14 and 15 where they may be secured by screws, nails or other fasteners. The devices 17 are preferably formed from inherently resilient material so that the sides of the doubled portion 19 will have a tendency to spring outwardly and thereby maintain a tight engagement with the sides of the recesses in the pieces 13 which are adapted to receive them.

Outer strips 21 and 22 and an intermediate strip 23 at each side of the frame provide the usual means of guiding the sashes 11 and 12 in their sliding movement. In the present instance I secure to the outer face of each intermediate strip 23 a somewhat wider but relatively thin strip 24, opposite side edges of which constitute flanges which are received in channels cut in the vertical side pieces of the sashes. Screws 25 are provided to secure the strips 24 to the intermediate strips 23 and upon certain of these screws are journaled rollers 26 which ride against adjacent faces of both sashes and thereby render the same easy to raise and lower. The strips 24 and the channels formed in the sashes to receive them provide a tortuous path through which the elements must pass to gain access to the interior of a structure in which the window is located and it has been found that a tortuous path so provided is effective to prevent such passage as is apparent.

Secured to and extending transversely of the upper transverse piece 14, and in line with the upper sash, is a strip 27, while secured to the sill 16, in line with the lower sash, is a similar strip 28, the latter strip being provided with transverse apertures 29 to permit rain or other water to drain from the inner to the outer side thereof. The upper rail of the upper sash is provided with a channel to receive the strip 27 when said sash is closed and similarly the lower rail of the lower sash is provided with a

channel to receive the strip 28 when this sash is closed. Strips 27, 28 together with the channels which receive them provide tortuous paths similar to and for the purpose of the tortuous paths produced by the strips 24.

In the modification illustrated in Figures 4, 5 and 6 the single sash 30 is shown as being hinged at 31 to the frame 10 and when in closed position abuts against stops formed of strips 32 and 33 and side strips 34, all of which are secured to the frame, the lower strip 33 having apertures formed therein similar to and for the same purpose as the apertures mentioned in connection with the lower strip in the first form of the invention. In the present instance the strips 32 and 34 are formed with tongue portions adapted to be received in channels cut in the sash frame as best illustrated in Figure 6. The lower strip 33, however, rests on a metallic member 35 the same extending the full width of said strip and including a doubled portion 36 disposed against the face of said strip facing the sash 30, so that the latter when swung closed will compress said doubled portion and thereby produce a tight joint at this point. Preferably the lower rail of the sash is cut away, as illustrated in Figure 5, so that when the sash is closed a portion of said strip 33 will be covered by the lower rail of the sash, and also the latter will cover the doubled portion of the metallic members.

From the foregoing description taken in connection with the accompanying drawings, it is believed that the construction, operation and advantages of my improved window structure will be clearly understood and while I have herein shown and described certain specific embodiments of my invention I do not wish to be limited thereto except in the manner indicated by the terms of the appended claims.

Having thus fully described my invention, what I claim as new, and desire to secure by Letters Patent, is:

1. In a window structure, a frame including a sill, a sash associated therewith, a strip 50 extending across the sill and adapted to

serve as an abutment for said sash, a metallic member underlying said strip and including a doubled portion disposed against the face of said strip and adapted to be compressed thereagainst during the closing movement of the sash, and said doubled portion being received within a cutout portion of said stile.

2. In a window structure, a frame having a sill, a sash associated therewith, a strip 60 secured to said sill, a metallic member underlying said strip and including a folded portion disposed substantially parallel with respect to one face of the strip, said strip having in its underface a plurality of transverse apertures, and a folded portion of said metallic member adapted to be compressed against said strip during the closing movement of said sash.

3. In a window structure, a frame of the 70 class described having therein a sash, a strip secured to the frame and against which the sash abuts when in a closed position, said strip being received within a cutout portion in the sash, a metallic plate secured to said frame beneath said strip, and said plate having a vertically extending folded portion adapted to be compressed between said sash and strip when the sash is in a closed position.

4. In a window structure, a frame including a sill, a movable sash associated therewith, a transverse strip secured to the face of the sill and extending the entire length thereof, a metallic member positioned between said strip and sill, said metallic member having a folded vertical portion, one part of which lies flush against the inner edge of said strip, the said strip having in its underface a plurality of transverse apertures, and the doubled portion of said metallic member being compressed against the strip during the closing movement of the sash.

In testimony that I claim the foregoing 95 I have hereunto set my hand at West Allis, in the county of Milwaukee and State of Wisconsin.

THOMAS L. JURASINSKI.
